UNITED STATES PATENT OFFICE.

ALFRED J. THOMAS, OF BRAINTREE, MASSACHUSETTS.

SHOE UPPER.

Original application filed August 29, 1923, Serial No. 660,044. Divided and this application filed February 12, 1924. Serial No. 692,423.

To all whom it may concern:

Be it known that I, ALFRED J. THOMAS, a citizen of the United States of America, and a resident of Braintree, in the county 5 of Norfolk, in the State of Massachusetts, have invented certain new and useful Improvements in Shoe Uppers, of which the following is a specification.

This invention relates to shoe uppers and 10 has for its object the production of a shoe upper with a corded edge, said corded edge being substantially the same thickness as the remainder of the upper.

The invention consists of an upper the 15 edge of which is skived on one side and has secured to its opposite face by a row of stitches the folded edge of a selvage edged tape with a cord in its fold, said tape having a single thickness extending beyond the edge 20 of the upper and folded over against the skived edge of the upper and secured thereto by another row of stitches.

The invention further consists of certain 25 novel features of construction and arrangement of parts which will be understood readily by reference to the description of the drawings and to the claims to be herein-after given.

For the purpose of illustrating the invention, one preferred form thereof is illustrated in the drawings this form having been 30 found to give satisfactory and reliable results although it is to be understood that the various instrumentalities of which the invention consists can be variously arranged and organized and the invention is not limited to the precise arrangement and organization of these instrumentalities as 35 herein shown and described except as required by the scope of the appended claims.

Of the drawings:

Figure 1 represents an elevation of a portion 40 of a shoe upper provided with a binding embodying the principles of the present invention.

Figure 2 represents a perspective of a portion 45 of the tape used in binding the upper.

Figure 3 represents a perspective of said 50 tape with an edge thereof folded over a cord.

Figure 4 represents a perspective of a portion 55 of the upper showing its skived edge.

Figure 5 represents a perspective of the

folded tape secured to the outer face of the upper.

Fig. 6 represents a similar view with one thickness of the tape folded over upon the skived edge of the upper, and

Fig. 7 represents a similar view with the lining of the upper applied thereto.

Similar characters indicate like parts throughout the several figures of the drawings.

In the drawings 10 is a portion of an upper having secured to an edge thereof a corded piping 11. This piping is formed from a tape 12 having selvage edges 13, 13'.

One edge 13 of the tape 12 is folded over a cord 14 the selvage edge 13 being in contact with the cord 14 when the fold has been completed.

When thus folded over, the folded tape 12 is secured to the outer face of the upper by 75 a row of stitches 15 close to the edge thereof.

The inner face of the upper is skived at 80 its edge as indicated at 16 in Fig. 4 prior to the securing of the tape 12 thereto.

When the tape 12 has been secured to the skived edge of the upper the folded edge 13 is beneath the upper while only a single thickness of said tape 12 extends beyond said edge as clearly shown in Fig. 5.

This single thickness of tape 12 is then folded over onto the skived portion 16 of the upper 10 and subsequently the lining 17 for said upper is placed over the inner face of the upper 10 and the single thickness of tape 12 upon the skived portion 16 of said upper.

The lining 17 and the tape 12 are then sewed together by a row of stitches 18 as shown in Fig. 7, said stitches 18 extending 95 into the space between the edge 13 and in-turned edge 19 of the upper.

When the edge 13 is secured to the body 100 of the tape by the row of stitches 15, these stitches will pass through portions of the cord 14 and prevent end movement thereof in the folded portion of the tape 12.

When the edge 19 of the upper is inturned with the single thickness of tape 12 folded over upon the skived inner face of the upper 105 the row of stitches 15 will be in the position indicated in Fig. 6 where they are hidden when the upper is viewed from the outer side thereof.

By skiving the inner face of the upper as 110

at 16 a space is created in which the single thickness of tape 12 may be positioned without increasing the thickness of the upper at this point.

5. This permits the lining 17 to be perfectly flat upon the inner face of the upper entirely free from any bulge therein at any point.

10. By making the corded tape in the manner described the cord 14 is securely held in the fold thereof and there is no necessity for the use of glue or other adhesive to retain the folded edges of the tape together.

15. Where glue or adhesive is used it causes much trouble during the subsequent stitching operations, getting into the barb of the needle and clogging the same and owing to its presence making the operation of stitching much more difficult. These objections 20 are entirely overcome in the present invention.

25. By using a tape with a selvage edge another objection is overcome as when strips of cloth are used folded over a cord and secured together by glue the edges are constantly unravelling and the unravelled threads become tangled up in the machines used to secure the corded tape to the upper.

30. Another advantage of the present invention is that the corded portion of the upper is no thicker than the body portion of the upper thus avoiding bulges in the lining which would cause much discomfort to the wearer of the shoe in which such uppers 35 were used.

35. If desired the single thickness of tape 12 positioned on the skived portion 16 may be united thereto by adhesive but where the tape 12 is provided with selvage edges 13, 40 13* this is not essential as the selvage edge 13 of the tape will prevent the edge from unravelling and consequently the stitches 15 will securely retain the corded tape in position upon the upper with the single thickness of tape 12 lying flat on the skived portion 16.

45. It is believed that the many advantages of the invention will be apparent without further description.

50. Having thus described my invention, I claim:

1. A shoe upper having secured to the edge of its outer face two thicknesses of the folded edge of a tape with a cord in its fold, said

tape having a single thickness which, with 55 a portion of the upper outside said row of stitches, is turned inwardly onto the inner face of said upper, and a lining superimposed upon the inner face of the upper and secured thereto and to said tape by another 60 row of stitches.

2. A shoe upper having an inturned edge and a lining on its inner face, a tape having a fold at one edge enclosing a cord, the two thicknesses of the folded tape being secured 65 to the outer face of the upper by a row of stitches, while a single thickness of said tape interposed between said upper and lining is secured thereto by another row of stitches.

3. A shoe upper having an inturned 70 skived edge and a lining on its inner face, a tape having a fold at one edge enclosing a cord, the two thicknesses of the folded tape being secured to the outer face of the upper by a row of stitches, while a single thickness 75 of said tape interposed between said upper and lining and bearing against said skived edge, is secured thereto by another row of stitches.

4. A shoe upper having an inturned 80 skived edge and a lining on its inner face, a tape having a fold at one edge enclosing a cord, the two thicknesses of the folded tape being secured to the outer face of the upper by a row of stitches, while a single thickness 85 of said tape interposed between said upper and lining and bearing against said skived edge, is secured thereto by another row of stitches, the first row of stitches also 90 passing through said cord.

5. A shoe upper having secured to the edge of its outer face two thicknesses of the folded edge of a selvage edged tape with a cord in its fold, said tape having a single thickness which, with a portion of the upper 95 outside said row of stitches, is turned inwardly onto the inner face of said upper, and a lining superimposed upon the inner face of the upper and secured thereto and to said tape by another row of stitches.

Signed by me at 746 Old South Bldg., Boston, Massachusetts, this 11th day of February, 1924.

ALFRED J. THOMAS.
